UNITED STATES PATENT OFFICE

ARTHUR M. TROGNER, OF MAPLEWOOD, NEW JERSEY, ASSIGNOR TO WIRED RADIO, INC., OF NEW YORK, N. Y., A CORPORATION OF DELAWARE

DESIGN FOR AN ESCUTCHEON FOR WIRED RADIO RECEIVER

Application filed March 29, 1930. Serial No. 35,061. Term of patent 14 years.

To all whom it may concern:

Be it known that I, ARTHUR M. TROGNER, a citizen of the United States, residing at Maplewood, in the county of Essex and State of New Jersey, have invented a new, original, and ornamental Design for Escutcheon for Wired Radio Receiver, of which the following is a specification, reference being had to the accompanying drawing, forming part thereof.

The drawing comprises Fig. 1 a plan view and Fig. 2 an elevation of an escutcheon for wired radio receiver, showing my new design.

I claim:

The ornamental design for an escutcheon for wired radio receiver, as shown.

ARTHUR M. TROGNER.
